UNITED STATES PATENT OFFICE

118,370

DESIGN FOR A LOCOMOTIVE BODY

John Gibson, Columbus, Ohio

Application February 14, 1939, Serial No. 82,987

Term of patent 7 years

To all whom it may concern:

Be it known that I, John Gibson, a citizen of the United States, residing at Columbus, in the county of Franklin and State of Ohio, have invented a new, original, and ornamental Design for a Locomotive Body, of which the following is a specification, reference being had to the accompanying drawing, forming part thereof.

Figure 1 is a top plan view of a locomotive body, showing my new design.

Figure 2 is a side elevational view thereof.

Figure 3 is a front elevational view thereof on a reduced scale.

Figure 4 is a front perspective view thereof on a reduced scale.

The opposite side of Figure 2 of the drawing is substantially the same as that shown.

I claim:

The ornamental design for a locomotive body, as shown and described.

JOHN GIBSON.
